DYNAMIC DEAERATOR HEATER

Henry J. Schneider, Quincy, Mass.

Application July 28, 1939, Serial No. 287,147

6 Claims. (Cl. 261—89)

My invention relates to water heaters and more particularly to a type of deaerator heater.

It is an object of my invention to provide a deaerator heater whereby the water will be spread over a substantial area and agitated for a sufficient time, whereby a dynamic action permits a greater liberation of air and oxygen or other impurities, which are a detriment to steam generation.

10 It is a further object of my invention to provide for heating the water, assisted by a dynamic force within the chamber.

In the present instance the water enters an upper chamber and is agitated, at various stages, a steam spray being applied at each stage whereby an amalgamation takes place between the water and steam. The water is heated gradually since the steam pressure is applied in the lower stage and passes through a steam nozzle and a 15 rotating wheel rigidly secured to the lower disk or shaft, revolving the circular disks within the chamber. The heated water will then pass to a storage space, free from impurities where it is covered with steam to prevent reabsorption of 20 any impurities, and the non-condensed vapor and impurities above the latter are passed out through the upper chamber into a condenser whereby the vapor is condensed and the impurities are expelled to the atmosphere.

25 30 The principal object of my invention therefore is a combined dynamic deaerator and water heater.

Other objects and novel features will appear as the description of the operation and construction of the device progresses.

In the drawing illustrating my preferred embodiment of the invention,

Figure 1 is a sectional elevation of the dynamic deaerator and water heater attached to the condenser.

Figure 2 is a sectional view on the line 2—2 of Figure 1.

Figure 3 is a sectional view on the line 3—3 of Figure 1.

45 Figure 4 is an enlarged elevational view on the line 4—4 of Figure 1.

Figure 4—a is a sectional view thereof.

Figure 5 is an enlarged sectional view on the line 5—5 of Figure 1.

50 Referring to the drawing and particularly to Figure 1, the heater is shown as comprising sections 1 to 4 suitably connected one above the other to define the dynamic deaerator and water heater which is provided with an exhaust pipe 6 directly connected to the condenser 5.

The dynamic deaerator and water heater may be composed of any number of stages and for the purpose of illustration, I have shown in sectional elevation, three stages 1—A, 2—A, and 3—A, each of which is composed of a circular perforated 5 plate, a revolving circular disk and a cylindrical baffle plate. These stages are identical in structure except that each stage varies in diameter and the side wall of the shell at the last stage is used as a baffle. Stage 1—A is shown as having a 10 circular plate 13 secured to a sleeve 12 and buttress plates 9, 10 and 11, the latter being fixed to the wall of the heater 1, as shown in Figure 3. A revolving perforated circular disk 14, as shown in Figure 4 is secured to an upright shaft 37 and 15 a cylindrical baffle plate 15 is secured by buttress plates 19 to the shell of the heater. The numeral 16 represents a pipe perforated as shown in Figure 4, which has a steam feed line 17 for supplying steam thereto to provide a steam spray in 20 stage 1—A.

Stage 2—A is of similar construction, shown in Figure 2, and includes a perforated circular plate 22 secured to a sleeve 21, the plate being supported by buttress plates 19. A revolving circular 25 disk 24 is provided, perforated as at 14', shown in Figure 4, and secured to shaft 37. A cylindrical baffle plate 23 is secured to radial buttress plates 26, the latter being secured to the shell of the heater, and the numeral 25 represents a steam 30 pipe having perforations corresponding to the perforations in pipe 16, and steam inlet pipe 17'.

Stage 3—A is shown, including a circular perforated plate 30 secured to a sleeve 29, supported by buttress plates 25, 27 and 28, as previously described and a revolving cylindrical disk 31 is secured to the shaft 37. The disk 31 is perforated to permit discharge of water upon the turbine wheel 33, the latter being secured by brackets 32 to disk 31. Steam is supplied through pipe 33 40 and nozzle 34 which revolves disks 14, 24 and 31, which are secured to shaft 37.

In Figure 5, I have shown the turbine wheel 33 and nozzle 34 as a sectional view illustrating the 45 approximate relation of the parts. The numeral 38 represents a shaft bearing secured to the upper face of a circular perforated plate 39, the latter being fixed within the casing of the heater and defining a storage space 42.

50 Numeral 41 represents a suction pipe between the reserve water chamber and suction pump, and pipe 40 represents a water drain.

The numeral 7 represents the feed water inlet 55 discharging on plate 8, shown in Figure 1, where-

by the water is spread out a distance through holes onto perforated plate 13 in stage I—A.

It should be noted that the disks 14, 24 and 31 have their peripheral edges inwardly directed and that the perforations 14' are formed circumferentially around the edge thus formed.

What I claim is:

1. A dynamic deaerator and water heater comprising a substantially cylindrical casing having an upper end including an outlet for steam vapor and impurities and a water inlet, said casing having at its lower end a steam inlet and a water outlet, a vertical rotatable shaft within the casing, a plurality of circular vertically spaced plates fixed to the shaft, said plates having an inwardly turned perforated edge, a perforated plate positioned above each of the first named plates, a perforated spreader plate concentric with the uppermost perforated plate and positioned beneath the water inlet, said spreader plate having a bearing complementary to the upper end of the shaft, a steam spray pipe beneath each of the circular plates, a steam turbine wheel connected with the lowermost circular plate, and said steam inlet having nozzles for discharge of steam against the turbine wheel whereby to rotate the shaft and associated plates.

2. The structure of claim 1, in which the circular plates, perforated plates and steam coils progressively increase in diameter in a downward direction.

3. The structure of claim 1, in which certain of the circular plates, perforated plates and coil include a circumscribing baffle plate.

4. A dynamic deaerator and water heater comprising a substantially cylindrical casing having an upper end including an outlet for steam vapor and impurities and a water inlet, said casing having at its lower end a steam inlet and a water inlet, a perforated horizontal partition wall in the casing, a bearing medially of the partition upon its upper side, a shaft rotatably mounted

within the bearing, a plurality of circular vertically spaced plates fixed to the shaft, said plates having an inwardly turned perforated edge, a perforated plate positioned above each of the first named plates, each of said last named plates having a bearing for the shaft, a circumscribing baffle plate connected to each of the perforated plates, buttress plates connected between the baffle plates and the wall of the casing, a perforated spreader plate concentric with the uppermost perforated plate and positioned beneath the water inlet, said spreader plate having a bearing complementary to the upper end of the shaft, a steam spray pipe beneath each of the circular plates, a steam turbine wheel connected with the lowermost circular plate, and said steam inlet having nozzles for discharge of steam against the turbine wheel whereby to rotate the shaft and associated plates.

5. The structure of claim 4, in which the circular plates, perforated plates and steam coils, progressively increase in diameter in a downward direction.

6. A dynamic deaerator and water heater comprising a substantially cylindrical casing having an upper end including an outlet for steam vapor and impurities and a water inlet, said casing having at its lower end a steam inlet and a water outlet, a vertical rotatable shaft within the casing, a plurality of circular vertically spaced plates fixed to the shaft, a perforated plate positioned above each of the first named plates, a perforated spreader plate concentric with the uppermost perforated plate and positioned beneath the water inlet, a steam spray pipe beneath each of the circular plates, a steam turbine wheel connected with the lowermost circular plate, and said steam inlet having a nozzle for discharge of steam against the turbine wheel to rotate the shaft and associated circular plates.
